DRAUGHT CHIMNEY TOP

Filed June 2, 1931

UNITED STATES PATENT OFFICE

1,940,566

DRAUGHT CHIMNEY TOP

John J. Schroeder, Philadelphia, Pa.

Application June 2, 1931. Serial No. 541,708

2 Claims. (Cl. 72—92)

This invention relates to an improved draught chimney top, and on to which a chimney extension can be attached if so desired, and one of the purposes of the invention is to reduce fire hazards and to eliminate mortar joints, which as a rule crumble and fall out and allow air to blow in the sides of the chimney reducing draught and causing possible fire hazards.

Another purpose is to provide a flue chimney top, constructed of any suitable plastic material such as terra cotta, cement or tiling material, such as may be made in various colors to simulate other materials on the building, and in providing a terra cotta, cement, or tile chimney top, there are no loose bricks to fall off the top of the chimney as in the cases where chimney tops are constructed of brick.

Another purpose is to provide a chimney flue lining constructed of any suitable material, such as cement, terra cotta or the like, and a further purpose is to extend this lining a substantial distance above the brick work of the chimney. In other words the chimney is extended above the slag or other roof substantially about two courses of brick, while the lining of cement or terra cotta or other material is extended a substantial distance above the brick work, the extension of the cement or terra cotta flue lining acting to telescopically fit into the chimney top of terra cotta or cement, a sufficient layer of mortar on the sides of the extended flue lining and on top of the brick work of the chimney, to provide secure bond between the chimney top and the chimney proper, hence preventing the chimney top from toppling over.

Another purpose is to provide, in a chimney, means whereby an extension can be mounted on the chimney top, the combined structure including means to prevent the chimney top as well as the extension from toppling to one side.

It is to be understood that the particulars herein given are in no way limitative, and that while still keeping within the scope of the invention, any desired modification of details and proportions may be made in the construction of the appliance according to circumstances.

The invention comprises further features and combination of parts to be hereinafter set forth, shown in the drawing and claimed.

50 In the drawing:—

Figure 1 is a view, showing the one or more courses of brick work of the chimney proper extending above the slag or other character of roof, illustrating the chimney top as applied.

55 Figure 2 is a vertical sectional view on line

2—2 of Figure 1, showing the structure and mounting of the chimney top.

Figure 3 is a sectional view on line 3—3 of Figure 1.

Figure 4 is a view showing the chimney top, 60 and an extension mounted on the top, illustrating means for holding the chimney top and the extension together and in such wise as to prevent toppling to one side.

Figure 5 is a sectional view, more clearly 65 showing the construction and mounting of the chimney top and its extension illustrated in Figure 4, also showing screw rods 15 for retaining the chimney top and its extension connected.

Referring to the drawing 1 identifies that portion of the chimney of the building that extends two or more courses of brick above the slag or other character of roof 2, whereas 3 identifies flue linings, which may be constructed of any suitable material preferably cement, terra cotta or the like. These linings 3 extend a substantial distance above the brick work of the chimney 1, and telescope into the flues or passages 4 of a chimney top 5.

The chimney top may be constructed of any suitable material preferably cement or terra cotta or the like, and in case of double chimney the chimney top is provided with a divisional wall 6. At the base of the chimney top 5 a ledge 7 is provided, and formed in the ledge are openings 8, which may receive bolts, as in the case where a chimney extension is mounted on the chimney top.

When the chimney top 5 is placed in position 90 with the flue linings 3 telescoping the flues or passageways 4 of the chimney top a layer of cement mortar or similar binding material is deposited on the top surface of the brick work of the chimney and against the extended parts 95 of the flue linings, so as to insure a secure bonding between the chimney top 5 and the extensions of the flue linings, said bonding material 9 acting to hold the chimney top in position and in such wise as to prevent the same from 100 toppling to one side.

Adjacent the upper portion of the chimney top 5 is a ledge 10 provided with openings 11. This ledge is formed a substantial distance below the upper margin 12 of the chimney top, in which case it is obviously possible to mount an extension 13 on the chimney top. This extension 13 may be made of any suitable material as cement or terra cotta, and it has a ledge 14 at its lower end and mates with the ledge 10, including a de- 110

posit of cement mortar or other bonding material between the two ledges and the sides of the chimney top 5, that is above the ledge 10, hence providing a secure bonding between the chimney top 5 and the extension.

Suitable elongated bolts 15 as shown in Figure 5 pass through the ledge 7, and upwardly through the ledges 10 and 14, for the purpose of further holding the chimney top and its extension firmly connected, the upper ends of the bolts or rods having holding nuts.

In the construction of a chimney top of this kind no flashing is used to prevent water from running down the sides of the chimney to the interior of the house, for the reason that the slag or other character of roof can be turned up under the projecting ledge 7, and in this way protecting the chimney below the roof. However flashing can be used if desired.

Suitable cable braces as identified at 17 may be used in the openings 11 if desired, for the purpose of additional bracing the chimney top in position.

The invention having been set forth, what is claimed is:

1. In a chimney and top structure therefor, a chimney extension protruding above a roof, a terra cotta chimney flue lining extending a substantial distance down into the chimney and a substantial distance above the chimney brick work, a chimney top of terra cotta having a flue the lower end of which receives the substantial length of extension of the terra cotta flue lining of the chimney, a secure plastic bonding material between the base portion of the chimney top and the brick work of the chimney extension and between the terra cotta flue extension and the interior passage of the chimney top to hold the chimney top and the chimney terra cotta flue lining elements together to insure a bonding joint, the base portion of the terra cotta chimney top having a marginal projecting ledge, which overlies and extends beyond said bonding joint and adapted to shed the water beyond said joint of bonding material, a second chimney top section telescopically fitting the upper extension of the first chimney top with a ledge at its lower end, a second bonding material including a single course of brick between the adjacent ledges, means for fastening the adjacent ledges together, the second chimney top section having a ledge at its upper end, and cable guy braces connected to the ledge at the upper end of the second chimney top section and in turn connected to the roof for reinforcing the entire construction in place.

said bonding joint and adapted to shed the water beyond said joint of bonding material, the upper end of said chimney top having a marginal ledge including a chimney top extension beyond the ledge adapted to substantially enter a second chimney top section, and cable guy braces connected to the ledge at the upper end of the chimney top and in turn adapted to be connected to the roof to retain the chimney top section in place.

2. In a chimney and top structure therefor, a chimney extension protruding above a roof, a terra cotta chimney flue lining extending a substantial distance down into the chimney and a substantial distance above the chimney brick work, a chimney top of terra cotta having a flue the lower end of which receives the substantial length of extension of the terra cotta flue lining of the chimney, a secure plastic bonding material between the base portion of the chimney top and the brick work of the chimney extension and between the terra cotta flue extension and the interior passage of the chimney top to hold the chimney top and the chimney terra cotta flue lining elements together to insure a bonding joint, the base portion of the terra cotta chimney top having a marginal projecting ledge, which overlies and extends beyond said bonding joint and adapted to shed the water beyond said joint of bonding material, a second chimney top section telescopically fitting the upper extension of the first chimney top with a ledge at its lower end, a second bonding material including a single course of brick between the adjacent ledges, means for fastening the adjacent ledges together, the second chimney top section having a ledge at its upper end, and cable guy braces connected to the ledge at the upper end of the second chimney top section and in turn connected to the roof for reinforcing the entire construction in place.
